UNITED STATES PATENT OFFICE.

WILLIAM M. BARBER, OF SOMERVILLE, MASSACHUSETTS.

PULP-DRYING MACHINE.

990,950.

Specification of Letters Patent.

Patented May 2, 1911.

Application filed August 6, 1909. Serial No. 511,549.

To all whom it may concern:

Be it known that I, WILLIAM M. BARBER, of Somerville, in the county of Middlesex and State of Massachusetts, a citizen of the 5 United States, have invented a new and useful Improvement in Pulp-Drying Machines, of which the following is a full, clear, and exact description, reference being had to the accompanying drawings, forming a part of 10 this specification, in explaining its nature.

My invention relates to a machine adapted to act primarily as a pulp drying machine, but which incidentally is adapted also to 15 form wet pulp into a sheet for producing leatherboard, so called, or cardboard.

The essential object of my invention is to 20 provide a machine capable of drying a large quantity of pulp in a relatively short space of time and which machine will operate to subject the wet pulp to such influence or to 25 the effect of such combined influences that a high percentage of the water in the pulp will be extracted from it and the pulp be formed into a sheet or compact mass in which form it can conveniently and economically be shipped.

In the machine embodying my invention it is my further object to provide for the 30 forming or molding of the wet pulp into a continuous sheet directly as the pulp comes from the mass and before the application of pressure to it and to then provide for the gradual compression of this sheet in such manner that a maximum amount of water 35 will be squeezed from it, a uniformity of thickness be maintained and the sheet eventually assume a smooth, finished and attractive appearance.

My invention comprises various elements 40 of construction and structural combination all of which features can best be seen and understood by reference to the drawings, in which—

Figure 1 shows the machine in side elevation. Fig. 2 is a longitudinal section of the machine, and Fig. 3 shows a portion of the machine in front elevation.

In the drawings:—The frame of the machine comprises the sections 1 and 2, which, 50 with their component parts, support different operating parts of the machine as will hereinafter be explained.

Referring to section 1 of the frame or that part located at the forward end of the machine where the wet pulp is first received, 55 attention is directed to the hopper 3 mount-

ed upon this portion of the frame. The wet pulp is emptied into this hopper from any suitable source of supply. The hopper comprises the sides 4—4 separated from one another a distance substantially commensurate with the width of the sheet to be formed.

5 represents the bottom of the hopper which connects with its respective sides and has an inclination of preferably about 45°. 65 This bottom 5 forms as it were a slide or chute over which the wet pulp may gravitate or flow out of the hopper.

6 is a gate or a movable end of the hopper arranged to coöperate with the slide 5 in such 70 manner that the pulp will gravitate or flow out of the hopper only in the form of a soft ribbon or sheet of pulp. In other words, the gate is so arranged that its bottom end will approach the bottom of the hopper or slide 75 5 (preferably at a point near the lower end thereof but removed therefrom), the gate acting to hold back the pulp within the hopper and allowing so much only of it to escape as may flow beneath the gate, the 80 height of the gate controlling of course the amount or thickness of the sheet of pulp. For the purpose of controlling the height of the gate it is arranged to slide in ways 7 formed on the respective sides of the hopper. 85 On the outside of the gate affixed to it are racks 8—8 engaging which are pinions 9—9 arranged upon a shaft 10 journaled in bearings 11 fixed to the frame and operated by a hand wheel 12 arranged at one end of the 90 shaft (see Fig. 3). It is obvious that as the hand wheel is moved in one direction or the other the gate will be moved up or down.

As the ribbon or sheet of pulp is formed and flows from the hopper it passes off the 95 lower end 13 of the slide 5, projecting beyond the point of the gate onto the top peripheral surface of a large drum 14 or rather onto a felt or canvas 15 wrapped around the drum. The drum 14 is mounted 100 upon a shaft journaled to turn in bearings 16 affixed to the frame and is so disposed that the drum will turn beneath the inclined chute leading from the hopper so that the sheet of pulp as it flows from the hopper 105 may become deposited on the down-turning top side of the drum or felt thereon at a point preferably just in front of the apex of the drum, the inclined chute 5 and its extension 13 being inclined in the direction 110 of the drum's rotation and coöoperating with the drum substantially tangentially. In

this connection attention is directed to the flanges 17 arranged on the drum at either end or side thereof, which flanges act to retain the sheet of pulp as it flows from the 5 hopper and prevent it from escaping laterally from the drum, in which connection it will be observed that the extension 13 of the slide extends down between these flanges on the drum in order that the lower end of 10 the slide may properly coöperate with the drum.

As the sheet is carried downwardly and around the drum or felt wrapped thereon it is subjected at first to a very slight but 15 gradually increasing degree of compression. Pressure is primarily administered by means of a perforated or wire belt 18 which renders partially around the drum and between which belt and the drum or felt thereon 20 the sheet is adapted to pass. Though the belt as it renders around the drum assists in compressing the sheet of pulp for extracting the moisture from it, yet this function is essentially performed by means of a 25 series of compression rolls with which the belt is reinforced or backed. The especial function performed by the belt is that of holding the sheet of pulp in place against the side of the drum or felt in order that 30 the sheet may withstand the otherwise disruptive influence exerted by the compression rolls which act to squeeze the moisture from the sheet, the moisture escaping through the perforations or openings in the belt. As 35 may best be seen by reference to Fig. 2, the belt 18 is an endless belt and renders in turn around the idler roll 19 arranged in the forward part of the machine in front of the machine, thence upwardly around an 40 idler roll 20, thence inwardly over an idler roll 21 and down around the drum, the belt encompassing preferably more than half of the drum. After leaving the drum the belt then renders over a pulley 22 which, as will 45 hereinafter be described, is one of the press rolls, thence back to the point of beginning. In referring to the disposition of these rolls over which the belt renders, attention is especially directed to the idler roll 21 over 50 which the belt renders just before passing onto and around the drum. This idler roll is located at a point adjacent to and just in front of the mouth of the hopper, the disposition of the roll being such that as the 55 belt renders off this idler roll onto the drum it will act to gradually compress the sheet of pulp coming from the mouth of the hopper as it is carried around on the drum or felt, the pressure at this point being so 60 slight that the sheet of pulp will not be retarded or held back causing a thickening of the sheet, but rather will be seized and carried forward without any action which will interfere with a proper uniformity in 65 the thickness of the sheet, the sheet after it

has once entered between the drum and the belt being then so compressed and held that it is less subjected to a disruptive influence. As for the roll 22 around which the belt 70 renders after passing around the drum, it will be observed that this roll is a roll presenting a relatively large bearing surface, on which account it acts to properly hold the belt drawn around and against the drum, the belt preferably being slack in the part 75 between the roll 22 and the roll 19. Attention is also directed to the fact that the belt is properly retained to render around the drum by means of its flanges 17, the belt fitting snugly against these flanges in order 80 that the sheet of pulp along the edges may be properly retained not only by the flanges themselves acting to form and hold the edges of the sheet but also by the belt at 85 these points.

As was before described, after the sheet has entered between the belt and the side of the frame that portion of the sheet held by the belt against the side of the drum is subjected to the influence of a series of compression rolls consisting primarily of a number of relatively small press rolls 23 successively arranged near one another so as to maintain an almost continuous bearing 90 stress against the belt for some considerable 95 distance around the drum in order that, especially at the point of primary compression, the belt will be so reinforced that the pulp interposed as it is between the belt and the drum will not strain the belt or cause 100 it to unduly bulge outwardly away from the drum at any point as might otherwise occur if the belt were not properly reinforced at this point. Moreover, should the pressure of the roll unduly distort the belt 105 the sheet will not be evenly compressed, less moisture will be extracted and the sheet will not have a uniformity of thickness, a point very desirable to be obtained. The rolls 110 23 are also adapted and arranged to the end that as the sheet forces the belt outwardly against the rolls they may act to compress the sheet with a gradually increasing degree of pressure. For the purpose of 115 properly maintaining the rolls and in order also that the position of all the rolls 23 may be simultaneously varied to accommodate sheets of different thickness, the rolls are arranged upon a frame 24 consisting essentially of side bars 25 in which the rolls 120 are arranged to turn. These side bars are curved so as to conform to the peripheral curve of the drum, or in other words, so that the rolls borne by them may properly coöperate with the belt around the drum. 125 The roll-carrying frame 24 is pivoted in the main frame section 1 of the machine at the point 26 below the drum, there being journaled in said main frame at said point a rod 27 to which the roll-carrying frame is 130

secured by arms 28 with the effect that the frame of rolls may be moved away from or toward the drum for varying the position of the rolls with respect to the drum. In 5 this connection it is to be noted that by reason of the pivoting of the frame at a point below the drum, as the frame of rolls is moved with respect to the drum the rolls will have a gradually increasing degree of 10 movement from the bottom roll upwardly. In other words, for any adjustment of the frame the top roll will have moved a considerably greater distance than the bottom roll. The advantage of this resides in the 15 fact that as the pulp enters between the belt and the drum it is very soft so in order not to disrupt it there is need of a much greater variation in the adjustment of the bearing roll at this point than farther along the 20 surface of the drum after the sheet has become compressed. The frame of rolls 25 may be adjusted with respect to the drum in any suitable manner. I have shown links 29 pivoted to each side bar of the frame. 25 These links pivotally connect with blocks 30 arranged to slide upon the frame 1 of the machine. Each of these blocks is controlled by a hand screw 31 fixed to turn in bearings 32 between which the blocks 30 slide as the screw is turned.

Another capability of the roll-carrying frame 24 resides in the fact that its side bars fit snugly adjacent to the flanges of the drum and the inner faces of the bars are flush with 35 the inner faces of the rolls carried by the frame with the effect that the bars assist in retaining the belt along the edges thereof on which account an even pressure is imparted along the edges of the sheet which 40 effect together with the retention imparted by the flanges of the drum give a finish to the edges of the sheet with no possible chance for the pulp to escape.

Beyond the rolls 23 I have provided an 45 other bearing roll 33. This roll is arranged between the flanges of the drum to bear against the same and the belt wound thereon and turns upon a shaft 34. This shaft is journaled to turn in the ends of weighted 50 levers 35 one on each side of the frame 1 of the machine, preferably on the outside thereof. The levers are each fulcrumed to a bracket 36 forming a part of the frame 1. The weighted arms of the respective levers 55 it is to be noted are relatively much longer than the power arms bearing the roll with the effect that the roll is yieldingly held to bear hard against the surface of the drum with the pressure varying with the positions of the weights on the lever arms. 60 The roll 22 over which the belt passes as it renders off the drum is also a pressure roll. This roll is adjustably supported by mounting the same upon a shaft 37 journaled to 65 turn on blocks 38 slidably arranged upon the

main section of the frame. These blocks are controlled by hand screws 39 extending through the blocks and fixed to turn in bearings 40 affixed to the frame. By turning the hand screws in one direction or the other the bearing position of the roll 22 may be varied with respect to the drum. 70

After the sheet of pulp has passed between the belt and the drum and been subjected to the action of the various pressure rolls before noted, it passes off the drum over the roll 22 and is then further compressed for extracting the moisture from it and hardening the sheet. The rolls for accomplishing this are arranged in section 2 of 80 the frame. There are shown two sets of rolls 41, 42 and 43, 44, respectively, and I prefer that they shall be heavy rolls capable of exerting an intense degree of pressure as the sheet is sufficiently hard to withstand such pressure. Of these rolls the lower rolls 42 and 44 of the respective sets of rolls are mounted on shafts 45 journaled to turn in fixed bearings 46 set in the frame. Inasmuch as it may be inexpedient or undesirable in the operation of the machine for the upper rolls 41 and 43 to rest normally in contact with the complementary rolls, inasmuch as the bearing stress of the upper rolls might be sufficient to disrupt the sheet 90 if fed between the rolls, I have arranged whereby each of the rolls 41 and 43 may be adjustably maintained in a position away from the under rolls yet in a position to exert a proper pressure upon the sheet. 100

The means I have provided consists in mounting each of the upper rolls upon a shaft 47 journaled to turn in boxes 48. These boxes are slidably mounted to slide in a vertical direction in ways 49 affixed to the frame. The upper ends of these ways are crossed by head bars or plates 50. Connecting with the respective boxes and extending upwardly through these head bars are supporting rods 51 having threaded shanks. 105 On these threaded shanks are arranged hand wheels 52 the hubs 53 of which bear against the head plates with the effect that as the hand wheels are turned the sliding boxes will be moved up or down and the rolls journaled in the boxes as aforesaid correspondingly moved or be adjustably maintained and positioned with respect to their complementary rolls. 115

The sheet of pulp is directed to pass over the bearing roll 22 and thence through the successive sets of press rolls by means of the felt 15. This felt, as before described, is passed around the drum, thence over the roll 22 and between the successive sets of press rolls 41, 42 and 43, 44, respectively, thence upwardly and around the upper end press, roll 43 and back to the drum. Being thus extended, the felt will carry the sheet of pulp contained between it and the belt over 120 125 130

the roll 22. The felt will then perform the function of a doctor in removing the sheet of pulp from the belt. The reason for this is that the belt is perforated while the felt 5 presents a smooth surface with the effect that the sheet of pulp will by the suction induced cling to the felt and be carried by it between the successive sets of press rolls and will not follow the belt.

10 Though the felt 15 performs the important function above described yet it performs also another useful function, that is, in relation to the drum.

By reason of the fact that the machine is 15 especially adapted to be used in connection with the drying of sulfite pulp, it is necessary that the drum be made of some material impervious to the action of the acids used in making the pulp. I accordingly

20 make the drum preferably of copper which presents a rather smooth surface. The disadvantage of such surface is that when the soft sheet of pulp is deposited upon the drum from the hopper, as before described,

25 the pulp is apt to run or become disrupted, if the surface be too smooth. By facing the drum with the felt, however, just the proper retentive surface is provided for holding the soft pulp as it is deposited upon the

30 drum. The felt presents also a better resisting surface for holding the pulp and maintaining the integrity of the sheet than if the sheet were held directly against the face of the drum. As far as these purposes are

35 concerned, however, apart from the function of the felt in carrying the pulp after it leaves the drum, it might as well be wrapped around the drum and affixed thereto.

40 Reference has been made to the fact that that portion of the perforated or wire belt passing from the roll 22 back to the idler roll 19 is slack. Such disposition of the belt is especially made in order that the slack 45 may extend down into a tank 54 containing water or other substance acting to wash the belt or neutralizing any acid that may collect on it and which otherwise might corrode or injure the belt. In this connection 50 I would explain that I prefer to make the belt of copper.

For the purpose of taking care of the water that may fall from the drum there is located beneath the drum on the top of 55 the receptacle 54 a cover 55 cylindrically concaved in form in order that the water as it falls from the drum onto the cover may be directed to pour out at either side thereof and be carried away. The cover 55 is 60 also so arranged as not to interfere with the proper passage of the belt through the tank.

Before referring to the operation of the machine, brief reference will be made to the mode of operating it:

65 In the base portion of section 1 of the

frame is arranged a driving shaft 56. Affixed to this shaft is a pinion 57 meshing with a gear 58 arranged upon the shaft on which the drum is mounted for rotating the drum. Meshing with the gear 58 is a gear 70 59 arranged upon the shaft 37 bearing the roll 22 and by which means this roll is positively rotated. Arranged also upon the shaft of the roll 22 is a sprocket wheel 60 around which renders a chain 61 connecting 75 with a sprocket 62 arranged on the shaft 34 of the press roll 33 for turning this roll. Arranged also on the shaft of the roll 33 is another sprocket 63 around which renders a chain 64 which connects with a sprocket 80 65 arranged on the shaft of the idler pulley 19 for turning this pulley. Arranged also on the shaft of this idler pulley is a sprocket 66 around which renders a chain 67 connecting with a sprocket 68 arranged upon the 85 shaft of the idler pulley 20. It will accordingly be seen that besides the drum practically all the rolls or pulleys around which the belt 18 is rendering are positively driven, which construction I prefer to employ. 90

As for the secondary mechanism consisting of the successive sets of press rolls, power is primarily applied to a driving shaft 69 journaled in the section 2 of the frame between the lower rolls of the successive sets 95 of press rolls. Mounted upon this shaft upon one side of the machine is a gear 70 which meshes respectively with gears 71 and 72 upon the shafts of the respective lower press rolls 42 and 44. The upper press rolls 100 41 and 43 are operated from off the lower press rolls by means of gears 73, 74 mounted upon the shafts of these respective rolls meshing with the gears 71 and 72 arranged upon the respective shafts of the lower rolls. 105

Referring now briefly to the operation of the machine: Assuming the machine has started, the gate controlling the hopper is opened when a thin loose sheet of pulp of substantially the same width as the sheet to be formed will slide out onto the top surface of the drum. The speed of the drum and operating parts should be such that there will be no disruption of the sheet at the point where it leaves the end of the 110 slide and meets the surface of the drum or felt on the drum, the speed being such as to take up the pulp thus deposited and carry it forward. The speed of the drum, however, should be such as to carry the pulp forward 115 in such manner that the soft sheet, loosely resting as it does on the top surface of the drum, will have no opportunity to run before it is engaged by the belt which acts to hold it in place against the drum. The sheet will then pass around the drum by and through the various sets of rolls in the manner before described. 120

I wish to include by the term "pulp" any material which can be used in the machine 130

though this expression is meant more specifically to refer to wood pulp.

By the term "felt" I wish to include any substance capable of performing the functions of the felt as above described. In fact I prefer to employ a canvas felt.

In further reference to the "felt" it should be understood that while the use of the felt has its advantages as above explained, yet it is not an indispensable element of the machine which is still properly operative even if the felt be entirely eliminated.

Having thus fully described my invention, 15 I claim and desire to secure by Letters Patent of the United States:—

1. In a machine of the character specified, the combination of a rotary drum, an endless belt arranged to render onto said drum, 20 thence around the same in part and off the same, a receptacle for containing loose pulp, means whereby pulp may gravitate from said receptacle in the form of a soft sheet, and said sheet be directed to pass between said belt and drum and be initially compressed by said belt rendering onto said drum, and means backing said belt and arranged whereby said belt may be reinforced to further compress the pulp passing 25 between it and said drum with a gradually increasing degree of compression continuing for an appreciable distance around said drum.

2. In a machine of the character specified, 35 the combination of a rotary drum, an endless belt arranged to render onto said drum, thence around the same in part and off the same, a receptacle for containing loose pulp, means whereby pulp may gravitate from said 40 receptacle in the form of a soft sheet, and said sheet be directed to pass between said belt and drum, and a series of press rolls backing said belt at successive points around the peripheral surface of said drum the first 45 one of which rolls is removed from said surface of the drum and the others of the rolls in relation to said first roll being arranged to gradually approach said surface of the drum whereby said belt will be reinforced 50 to compress the pulp passing between it and said drum with a gradually increasing degree of compression continuing for an appreciable distance around said drum.

3. In a machine of the character specified, 55 the combination of a rotary drum, an endless belt arranged to render onto said drum, thence around the same in part and off the same, a receptacle for containing loose pulp, means whereby pulp may gravitate from 60 said receptacle in the form of a soft sheet, and said sheet be directed to pass between said belt and drum and be initially compressed by said belt as it renders onto said drum, and a series of press rolls backing 65 said belt at successive points around the

peripheral surface of said drum the first one of which rolls is removed from said surface of the drum and the others of the rolls in relation to said first roll being arranged to gradually approach said surface of the 70 drum whereby said belt will be reinforced to compress the pulp passing between it and said drum with a gradually increasing degree of compression continuing for an appreciable distance around said drum. 75

4. In a machine of the character specified, the combination of a rotary drum, an endless belt arranged to render onto said drum, thence around the same in part and off the same, a hopper for containing pulp located 80 above said drum, means whereby pulp in said hopper may gravitate therefrom in a soft sheet and the sheet be directed onto said drum to be carried forward thereby as the drum is rotated to pass between said 85 belt and drum, and a series of press rolls backing said belt at successive points around the peripheral surface of said drum the first one of which rolls is removed from said surface of the drum and the others of the rolls 90 in relation to said first roll being arranged to gradually approach said surface of the drum whereby said belt will be reinforced to compress the pulp passing between it and said drum with a gradually increasing degree 95 of compression continuing for an appreciable distance around said drum.

5. In a machine of the character specified, the combination of a rotary drum, an endless belt arranged to render onto said drum, 100 thence around the same in part and off the same, a hopper for containing pulp located above said drum, means whereby pulp in said hopper may gravitate therefrom in a soft sheet and the sheet be directed onto 105 said drum to be carried forward thereby as the drum is rotated to pass between said belt and drum and be initially compressed by said belt rendering onto said drum, and a series of press rolls backing said belt at 110 successive points around the peripheral surface of said drum the first one of which rolls is removed from said surface of the drum and the others of the rolls in relation to said first roll being arranged to gradually 115 approach said surface of the drum whereby said belt will be reinforced to compress the pulp passing between it and said drum with a gradually increasing degree of compression continuing for an appreciable distance around said drum. 120

6. In a machine of the character specified, the combination of a rotary drum, a belt rendering around said drum in part, means whereby pulp may be fed to pass between 125 said belt and drum as said drum is rotated, a series of press rolls backing said belt, a frame supporting said rolls, and means whereby the position of said frame and rolls may be adjustably changed. 130

7. In a machine of the character specified, the combination with a rotary drum, of an endless perforated wire belt arranged to pass onto said drum, thence around the peripheral surface thereof in part and off the same, a receptacle for containing loose pulp, means whereby pulp may gravitate from said receptacle in the form of a soft sheet, and said sheet be directed to pass between said belt and drum, and means reinforcing said belt to compress said sheet of pulp with a gradually increasing degree of compression.

8. In a machine of the character specified, 15 the combination with a rotary drum, of an endless perforated wire belt arranged to pass onto said drum, thence around the peripheral surface thereof in part and off the same, a hopper for containing pulp located above said drum and coöperating therewith in a manner whereby pulp in said hopper may gravitate therefrom in a continuous sheet in substantially the direction of the drum's rotation and the sheet be deposited on said drum to be carried forward thereby and pass between said belt and drum, and means reinforcing said belt to compress said sheet of pulp with a gradually increasing degree of compression.

9. In a machine of the character specified, the combination of a rotary drum, an endless belt running onto said drum, thence bent to pass around a part of the drum and off the same, means for positively driving said belt whereby it may draw snugly against that portion of the drum over which it renders, a receptacle for containing loose pulp, means whereby pulp may gravitate from said receptacle in the form of a soft sheet, 35 and said sheet be directed to pass between said belt and drum as the drum is rotated, and means reinforcing said belt and retaining it to compress the pulp passing as aforesaid between the belt and drum with a gradually increasing degree of compression.

10. In a machine of the character specified, the combination of a rotary drum, a belt running onto said drum, thence bent to pass around a portion of the drum and off 50 the same, a pulley over which said belt renders as it passes off said drum, means for positively driving said pulley, means whereby pulp may be fed to pass between said belt and drum as the drum is rotated, and means 55 backing said belt whereby the belt may be reinforced to compress the pulp passing between it and said drum with a gradually increasing degree of compression.

11. In a machine of the character specified, 60 the combination of a rotary drum, a belt running onto said drum, thence bent to pass around a part of said drum and off the same, a pulley over which said belt renders prior to its passing onto said drum, a pulley over which said belt renders as it passes

off said drum, means for positively driving said drum, means for positively driving each of said pulleys, means whereby pulp may be fed to pass between said belt and said drum as the drum is rotated; and a series of press rolls coöperating with said belt at points between said pulleys for reinforcing said belt to compress the pulp passing between the belt and drum with a gradually increasing degree of compression.

12. In a machine of the character specified, 70 the combination of a rotary drum, a belt rendering around the same in part, a hopper for containing pulp located above said drum, means whereby pulp in said hopper may be directed to gravitate therefrom in a continuous sheet in substantially the direction of the drum's rotation and the sheet be initially deposited on the top surface of said drum at a point in front of the apex thereof on the down-turning side of the drum and be carried forward thereby as the drum is rotated to pass over said drum between said belt and drum.

13. In a machine of the character specified, 75 the combination of a rotary drum having flanges at either end thereof, a hopper for containing pulp located above said drum, a slide leading from the mouth of said hopper between the flanges of said drum and coöperating with said drum at a point in front of the apex thereof on the down-turning side of the drum whereby pulp flowing from said hopper by the way of said slide may be deposited on the drum at the point aforesaid and be carried forward by the drum as it is rotated, and a belt rendering around said drum in part between the flanges thereof, said belt being adapted and arranged to pass onto said drum at a point just in front 100 of the slide coöperating therewith as aforesaid for gradually compressing the pulp deposited on the drum from said slide as it enters to pass between said belt and drum.

14. In a machine of the character specified, 105 the combination with a rotary drum, of a felt wrapped around said drum, a belt adapted and arranged to pass onto said drum, thence around a portion thereof faced with said felt and thence off said drum, means whereby pulp may be fed to pass around said drum between said felt and belt and be initially compressed by said belt, said belt acting also to hold the sheet of pulp in place against said felt as it passes around said drum, and means for further compressing the sheet of pulp so held against said drum with a gradually increasing degree of compression.

15. In a machine of the character specified, 125 the combination with a rotary drum, of an endless felt wrapped around said drum and passing onto and off the same, an endless belt arranged to pass onto said drum, thence around a portion thereof faced with

- said felt and thence off said drum, means whereby pulp may be fed to pass around said drum between said felt and belt and be initially compressed by said belt, said belt 5 acting also to hold the sheet of pulp in place against said felt as it passes around said drum, means for further compressing the sheet of pulp so held against said drum with a gradually increasing degree of compression, a roll over which said felt and belt render after the compression of said sheet of pulp as aforesaid, and means for arranging said felt and belt whereby they may separate after passing off said roll.
- 10 16. In a machine of the character specified, the combination with a rotary drum, of a set of press rolls arranged beyond said drum, a felt passed around said drum and the upper one of said set of press rolls, an endless belt rendering onto, over and thence off from a portion of said drum faced with said felt, means comprising in part a roll located between said drum and said set of press rolls over which roll said felt and belt 15 are adapted to pass, means for feeding pulp to pass in a sheet over said drum between said belt and felt, and means for compressing said sheet during said passage.
- 20 17. In a machine of the character specified, the combination of a rotary drum, a hopper for containing pulp located above said drum and coöperating therewith in a manner whereby pulp in said hopper may 25 gravitate therefrom in a continuous sheet in substantially the direction of the drum's rotation and the sheet of pulp be deposited on the top surface of said drum at a point in front of the apex thereof on the down-
- turning side of the drum and be carried forward thereby as the drum is rotated, a belt 40 coöperating with said drum just in front of the point where said drum receives the deposited pulp as aforesaid, whereby the belt may initially compress said sheet of pulp, and which belt thence passes around said drum in part and off the same whereby the sheet of pulp after the initial compression thereof by said belt may pass around the drum between said drum and belt to be retained by said belt against said drum, and means whereby a further gradual compression of said sheet of pulp may be effected 45 during its passage over said drum.
18. In a machine of the character specified, the combination with a rotary drum, of a felt wrapped around said drum, a belt 50 adapted and arranged to pass onto said drum, thence around a portion thereof faced with said felt and thence off said drum, a hopper located above said drum and coöperating therewith in a manner whereby pulp in said hopper may gravitate therefrom in a continuous sheet and be deposited to pass between said belt and felt whereby it may be initially compressed by said belt, 55 said belt acting also to hold the sheet of pulp in place against said felt as it passes around said drum, and means for effecting a further gradual compression of the sheet of pulp during its passage around said 60 drum.

WILLIAM M. BARBER.
